UNITED STATES PATENT OFFICE.

EDWARD RATHBUN, OF TOLEDO, OHIO.

ENGINE.

1,073,629.

Specification of Letters Patent. Patented Sept. 23, 1913.

Original application filed May 29, 1908, Serial No. 435,779. Divided and this application filed July 5, 1912. Serial No. 707,840.

To all whom it may concern:

Be it known that I, EDWARD RATHBUN, a citizen of the United States of America, and a resident of Toledo, county of Lucas, and

5 State of Ohio, have invented certain new and useful Improvements in Engines, of which the following is a specification.

My invention relates to the jackets of gas engines and other engines, requiring cooling 10 of their cylinders, and comprises an engine cylinder, particularly a substantially horizontal engine cylinder, having a cylinder jacket divided horizontally into a plurality of compartments, at different levels respectively, 15 and a head jacket, all connected in such manner as to receive the cooling fluid successively, as hereinafter described.

In the water cooling of the cylinders of large gas engines and the like, having cylinder jackets and head jackets (which are usually directly connected), considerable difficulty is experienced from too high temperature of the water in the head jacket; and, in the case of large horizontal cylinders, since 20 the jacket water at the top of the cylinder will obviously be much warmer than that at the bottom, when the cylinder jacket is in one compartment only, as is usual, there is considerable difference in temperature between the top and the bottom of the cylinder, which not infrequently leads to "bowing" or actual deformation of the cylinder with consequent material increase in engine 25 friction and increased liability to excessive wear, cutting, and even sticking of the piston.

According to my invention, I divide the cylinder jacket into a plurality of compartments, at different levels, passing the water from the head jacket into one of these compartments and thence into another, so substantially equalizing the temperature of different parts of the cylinder.

The objects of my invention are to cool 30 gas engine cylinders, particularly large horizontal or substantially horizontal engine cylinders, and the like, more efficiently, and to avoid uneven heating of the different sides of the cylinder and consequent distortion.

I will now proceed to describe my invention with reference to the accompanying 35 drawings and will then point out the novel features in claims.

In the drawings: Figure 1 shows a central vertical longitudinal section of the cylinder 40 and associated parts of a horizontal type

gas engine, having a head jacket and a two-part cylinder jacket connected as above described. Fig. 2 shows a transverse section of said cylinder.

In the drawings, 15 designates the engine 40 cylinder, 16 the cylinder head, 17 the piston, 18 the connecting rod, 19 the head jacket, 20 the admission port thereof, and 21 the discharge port thereof.

22 and 23 designate lower and upper compartments into which the cylinder jacket is divided by horizontal ribs 24; 25 designates a duct connecting said discharge port 21 of the head jacket with the admission port 26 of the upper compartment 23 of the cylinder 70 jacket, and 27 designates a duct connecting the discharge port of compartment 23, such discharge port being located at the top of compartment 23, with the admission port of compartment 22; the admission port of compartment 22 being located at the bottom of such compartment.

28 designates the discharge port of the compartment 22.

The admission port of compartment 23, 80 besides being located at about the bottom of that compartment, is located near one end of that compartment, preferably the head end, as shown, while the discharge port of compartment 23 is located near the opposite 85 end of that compartment 23. The admission port and discharge port of compartment 22 are located at opposite ends of that compartment.

It will be seen that cooling water passes 90 first through the head jacket 19 into the lower portion of the upper compartment 23 of the cylinder jacket, and thence passes through compartment 23 to the upper portion thereof, and thence through duct 27 95 into the lower portion of compartment 23 and through compartment 22 to the opposite end thereof, and thence out. In general, water will be circulated positively through these jackets either by means of a pump, or as a result of the water being discharged at lower pressure than that at which it is received. I do not illustrate such means for positive circulation, as they are well known.

The head of the engine cylinder is naturally the part exposed to the greatest heat, and it will be observed that it is into the jacket of this part that the cooling water first enters. In large horizontal engines, 100 wherein the cylinder jacket is one compart- 110

ment only, it frequently happens that the water in the lower portion of this jacket is materially cooler than the water in the upper portion of such jacket, due to the natural tendency of warm water to rise and colder water to descend. The result of this is that the lower portion of the cylinder is maintained at a lower temperature than the upper portion of the cylinder. According to 10 my invention this uneven heating of the engine cylinder, which, if it occurs, frequently leads to warping, is obviated, in that the water is discharged from the head jacket into the upper compartment 23 of the cylinder 15 jacket, and thence from the compartment 23 into the compartment 22 of the cylinder jacket. The hottest portion of the cylinder wall included within compartment 22 is therefore closely adjacent to the coldest part 20 of the cylinder wall included within jacket 23; and since these parts are so closely adjacent, the flow of heat through the walls of the cylinder keeps these parts at nearly the same temperature. Furthermore, since the 25 water from the upper portion of compartment 23 passes directly into the lower compartment 22, the temperature of the lower portion of the cylinder wall is kept at practically the same temperature as the upper 30 portion of the cylinder wall.

The connection of the upper portion of the head jacket to one of the compartments of the cylinder jacket obviates the pocketing of steam in the head jacket; and the connection 35 of the upper portion of the compartment 23 of the cylinder jacket to compartment 22 of that jacket, obviates pocketing of steam in compartment 23; while the connection of the upper portion of compartment 22 to the discharge 28 obviates pocketing 40 of steam in compartment 22.

This application is a division of my application Serial No. 435,779, filed May 29, 1908.

45 What I claim is:—

1. A jacketed engine cylinder having a head jacket and having also a cylinder jacket surrounding the cylinder only and divided into a plurality of compartments 50 arranged at different levels, means for connecting the head jacket to one of said cylinder jacket compartments, and means for connecting one such cylinder jacket compartment to another cylinder jacket compartment.

55 2. A jacketed engine cylinder having a head jacket and having also a cylinder jacket surrounding the cylinder only and divided into a plurality of compartments 60 arranged at different levels, means connecting the head jacket to an upper compartment of the cylinder jacket, and means con-

necting such compartment of the cylinder jacket to a lower compartment of such cylinder jacket.

65

3. A jacketed engine cylinder having a head jacket and having also a cylinder jacket surrounding the cylinder only and divided into a plurality of compartments arranged at different levels, means connecting the head jacket to the lower portion of an upper compartment of the cylinder jacket, and means connecting the upper portion of such compartment of the cylinder jacket to the lower portion of a lower compartment 75 of such cylinder jacket.

70

4. A substantially horizontal engine cylinder comprising a head jacket and a cylinder jacket, the latter divided horizontally into a plurality of compartments arranged at different levels, means connecting the head jacket to an upper compartment of the cylinder jacket, and means connecting such upper portion of the cylinder jacket to a lower compartment of the cylinder jacket.

80

5. A substantially horizontal engine cylinder comprising a head jacket and a cylinder jacket, the latter divided horizontally into a plurality of compartments arranged at different levels, means connecting said head jacket to the lower portion of an upper cylinder jacket compartment, near one end of that compartment, and means connecting the upper portion of such upper cylinder compartment at a point near the opposite end of such upper compartment, to the lower portion of a lower cylinder jacket compartment.

90

6. A substantially horizontal engine cylinder, comprising an encircling jacket divided horizontally into a plurality of compartments, at different levels, an upper compartment having an inlet connection and means connecting such upper compartment to a lower compartment.

100

7. A substantially horizontal engine cylinder, comprising an encircling jacket divided horizontally into a plurality of compartments, at different levels, an upper compartment having near its bottom and near one end an inlet connection, and means connecting the upper portion of such upper compartment, at a point near the opposite end of such upper compartment, to the lower portion of a lower compartment, such lower compartment having near its top a discharge connection.

110

115 In testimony whereof, I have signed this specification in the presence of two subscribing witnesses.

EDWARD RATHBUN.
